CLAIM

The ornamental design for a robotic vacuum with a user interface, as shown and described.

DESCRIPTION

FIG. 1 is a top plan view of a robotic vacuum with a user interface;

FIG. 2 is a top plan view of the a robotic vacuum with a user interface; and,

FIG. 3 is a top perspective view of the a robotic vacuum with a user interface.

The broken lines illustrate portions of a robotic vacuum with a user interface and form no part of the claimed design.
